UNITED STATES PATENT OFFICE.

FREDERICK B. BROWN, OF SAN FRANCISCO, CALIFORNIA.

ARM AND SHOULDER BRACE.

1,257,297.

Specification of Letters Patent. Patented Feb. 19, 1918.

Application filed July 30, 1917. Serial No. 183,448.

To all whom it may concern:

Be it known that I, FREDERICK B. BROWN, a citizen of the United States, residing at the city and county of San Francisco and 5 State of California, have invented new and useful Improvements in Arm and Shoulder Braces, of which the following is a specification.

This invention relates to an apparatus 10 which is especially designed to support in any desired position the arms and shoulders of persons who have been injured so as to be incapable of properly supporting the injured members or parts.

15 The invention consists of a jointed framework of rigid material, belts and connecting supporting straps, a brace or standard pivoted at the top, so that it may swing about its pivots, jointed arms so connected 20 with the standard and with each other that the arms may be moved to dispose the supported member at different angles and positions, and means for locking the parts.

It also comprises details of construction 25 which will be more fully explained by reference to the accompanying drawings, in which—

Figure 1 is a side view showing the application of the device.

30 Fig. 2 is an enlarged sectional view of the upper joint.

Fig. 3 is a plan view of the elbow joint.

Fig. 4 is a plan view of the assembled device.

35 Accidents frequently occur in which shoulder bones and joints and the upper portion of the arm are seriously damaged, and for the purpose of holding these parts in position while they are healing, it has 40 been necessary to place them in a plaster cast, preventing all movement for a very considerable length of time.

It is the object of my invention to provide a light, easily-attached apparatus which 45 will serve to retain the parts in any desired and sufficiently rigid position, while at the same time allowing for adjustments from time to time as may be found desirable or necessary. In carrying out my invention I 50 employ a harness which is so designed as to fit the body of the wearer and to form a support for the apparatus.

As shown in the present case, A is a belt fitting around the body having a strap 2 55 extending diagonally across the shoulder and another counter-strap 3 extending in

the other direction and connected at the front and back with the belt. The apparatus consists of a rigid standard 4, which may be of light sheet metal or angle iron 60 sufficiently rigid for the purpose. This forms a standard which may be secured, as at 5, at the lower end by a suitable belt attachment in which this end is fixed. The upper end is pivoted in a sleeve, as shown 65 at 6, and this allows the sleeve to swing from the front toward the back and thus move the arm supports about the shoulder joint without too much strain on said joint. A thumb screw 6^a serves to lock the sleeve 70 at any desired point. A suitable protecting pad 4^a is interposed between the standard and the body and envelops the shoulder and contiguous parts.

The arm portion of the apparatus 75 consists of plates 7 and 8, preferably made concavo-convex, and which may be padded, if desired, so that the upper and lower portions of the arm may rest, one in each of these plates. The upper plate is joined to 80 the sleeve 6 by a joint, as shown at 9, and this joint has also combined with it a rotary ratchet joint 10 which allows this portion of the arm to be raised or depressed, and by means of a spring-pressed latch 11, engaging 85 the ratchet, it may be held in any desired position relative to the body.

A joint between the upper and lower plates is also provided, as shown at 12, and this allows the forearm to be raised and 90 moved independently of the upper arm. The end of the lower plate may be strapped or otherwise secured at the wrist in such a manner as to cause the arm and the plate to be moved in unison and held together. 95 The elbow joint is preferably made with two plates, one circumferentially slotted, as at 13, and a pivot screw passing through one plate is adapted to lock upon the other and thus hold this joint in the required position. 100 Clamping screws 14 pass through the slots and serve to lock the joint firmly.

By means of these joints it will be seen 105 that the arm may be raised about the shoulder to any desired angle therewith and retained in place. It will also be seen that the forearm may be turned about its joint from a position in line with the upper arm to a line substantially at right angles therewith.

In order to extend the arm sections and 110 extend the muscles or ligaments, when neces-

sary, the plates to which the arm supports are fixed are formed with slotted sections 15 with clamp screws passing through. By loosening these screws the sections may be 5 extended or shortened, as desired, and fixed in place. An angle plate 16 is supported from the pivot 12 and is turnable with relation to the arm plates. If it is desired to stretch the muscles or ligaments of 10 either part, that part may be strapped or secured to the upright portion of the angle plate 16 and thus retain it in place while the portion 15 is properly extended.

Having thus described my invention, what 15 I claim and desire to secure by Letters Patent is—

1. A shoulder and arm support and brace, comprising jointed extensions beneath the upper arm and the forearm respectively, 20 a standard upon which the said extensions are carried, swivel supports at the end of said standard allowing the arm to be turned horizontally, and a joint at the shoulder by which the arm and its supporting plates 25 may be set at any desired angle.

2. In a shoulder and arm support and brace, a belt truss fixed to the body having pivotal supports near the shoulder, a standard with a pivot turnable in said support, arm plates 30 upon which the upper and lower arm are independently supported, said plates being jointed at their intersection and capable of being turned to different relative angles, a ratchet joint and locking mechanism at the

junction of the upper arm plate and the 35 standard, and means to lock said joints.

3. In an apparatus of the character described, a rigid brace, means securing it to the body, an upper arm support, a sleeve turnable about the upper end of the brace, 40 a ratchet joint carried upon the sleeve and adapted to vertically adjust the arm support, and means to lock the parts.

4. In an apparatus of the character described, a brace secured to the body, an arm 45 support with a sleeve turnable about the upper end of the brace, a vertically turnable ratchet and lock upon the sleeve, and slotted plates with thumb-screws whereby longitudinal extension of the arm plates and 50 supported member may be effected.

5. In an apparatus of the character described, a brace, means connecting it with the body, a horizontally and vertically movable joint at the upper end of the brace, longitudinally adjustable arm supporting plates 55 connected and movable with said joint, joints between the upper and forearm plates, and an angle elbow plate adjustable with relation to the elbow joint.

In testimony whereof I have hereunto set my hand in the presence of two subscribing witnesses.

FREDERICK B. BROWN.
